UNITED STATES PATENT OFFICE

134,556

DESIGN FOR A LADY'S SUIT

Fannie Sussman, Lawrence, N. Y.

Application November 19, 1942, Serial No. 108,820

Term of patent 3½ years

To all whom it may concern:

Be it known that I, Fannie Sussman, a citizen of the United States and a resident of the city of Lawrence, in the county of Nassau and State of New York, have invented a new, original, and ornamental Design for a Lady's Suit, of which the following is a specification, reference being had to the accompanying drawing, forming a part thereof.

Fig. 1 is a front view of a suit showing my design.

Fig. 2 is a rear view of the suit shown in Fig. 1.

I claim:

The ornamental design for a lady's suit, substantially as shown.

FANNIE SUSSMAN.
